US00D959580S

(12) **United States Design Patent** (10) **Patent No.:** **US D959,580 S**
Lagreee (45) **Date of Patent:** **** Aug. 2, 2022**

(54) **EXERCISE MACHINE**(71) Applicant: **Lagree Technologies, Inc.**, Chatsworth, CA (US)D362,700 S 9/1995 Breibart
5,518,483 A 5/1996 Oswald
D382,319 S 8/1997 Gerscheske
(Continued)(72) Inventor: **Sebastien Anthony Louis Lagree**, Chatsworth, CA (US)

FOREIGN PATENT DOCUMENTS

WO 2004096376 A1 11/2004

(73) Assignee: **Lagree Technologies, Inc.**, Chatsworth, CA (US)

OTHER PUBLICATIONS

(***) Term: **15 Years**Balanced body, announced 2010 [online], [site visited May 3, 2022]. Available on internet, URL: https://www.amazon.com/Total-Gym-Fitness-Dynamic-Abdominal/dp/B0743HWSGD/ref=sr_1_16?dchild=1&keywords=CORE+TRAINER&qid=1634594852&sr=8-16 (Year: 2010).*(21) Appl. No.: **29/829,043**

(Continued)

(22) Filed: **Mar. 2, 2022**

FIG. 1 is a rear perspective view of an exercise machine showing my new design;

FIG. 2 is a front perspective view thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a rear view thereof.

The broken line portions of the drawings are included to show unclaimed subject matter and form no part of the claimed design.
